UNITED STATES PATENT OFFICE.

JOHN FLINK, OF PHILADELPHIA, PENNSYLVANIA.

AIRSHIP.

1,237,318.

Specification of Letters Patent. Patented Aug. 21, 1917.

Application filed October 10, 1916. Serial No. 124,890.

To all whom it may concern:

Be it known that I, JOHN FLINK, a citizen of the United States, residing at Philadelphia, in the county of Philadelphia and State of Pennsylvania, have invented new and useful Improvements in Airships, of which the following is a specification.

This invention relates to improvements in airships, the primary object of the invention being to provide an airship having series of beating wings on opposite sides of its longitudinal center, each consisting of longitudinally extending sets of lifting propellers rotatable at right angles to the line of flight, the propellers of the opposite series, being rotatable in opposite directions to secure efficient balancing of the thrust pressures and lifting effect, the propellers of the different sets being automatically controlled for a feathering action, whereby on the working motion of each propeller the propeller blades will be turned to a working position, while on the non-working motion of each propeller the blades will be turned edgewise to diminish air resistance.

A further object of the invention is to provide a construction of airship of the character described which is adapted to ascend or descend in a straight path, to hover over any given point, and to be steered and controlled in a vertical plane by varying the relative speeds of the series of propellers, thus allowing the ship to be balanced, banked and steered with efficiency.

A further object of the invention is to provide a novel construction of drive mechanism for actuating a driving propeller and also operating the lifting propellers, the said drive mechanism being so constructed as to admit of the different series of propellers being driven at the same or different speeds and also to admit of the driving propeller to turn into and out of action at will.

A still further object of the invention is to provide an airship of simple construction in which one or more, preferably two, driving motors will be employed for transmitting power to the working parts.

A still further object of the invention is to provide one or more supporting planes or surfaces having folding wings which may be conveniently thrown into and out of operation at will by power from the drive mechanism.

With these and other objects in view, the

invention consists of the features of construction, combination and arrangement of parts hereinafter fully described and claimed, reference being had to the accompanying drawings in which:—

Figure 1 is a front elevation of an airship constructed in accordance with my invention.

Fig. 2 is a side elevation of the same. 65

Fig. 3 is a sectional plan view on line 3—3 of Fig. 2.

Fig. 4 is a face view of one of the cam disks for feathering a series of propeller blades. 70

Fig. 5 is a cross section through the casting hub of one of the sets of propeller blades.

Fig. 6 is a vertical longitudinal section through the same. 75

Fig. 7 is a horizontal section through the bow portion of the car, showing the drive gearing.

Fig. 8 is a plan view of one of the supporting planes. 80

Referring now more particularly to the drawing, 1 designates a boat-shaped car or body, provided with wheels 2 or other suitable supporting means on which the same may rest upon the surface of the ground. 85 Carried by and rising from this car or body is a framework 3 of suitable construction provided with bearings for a pair of longitudinally extending parallel shafts 4 and 5 upon which are respectively mounted longitudinal sets or series 6 and 7 of rotary beaters, each consisting of a plurality of sets of rotary propeller blades. These longitudinal series of propellers are arranged on opposite sides of the longitudinal center of 90 the machine, so that in the action of the series of propellers the lateral thrust pressures of one series will be counteracted by the lateral thrust pressures of the other series, whereby the ship will be kept trim or 95 in a balanced position while in flight.

Each set of propellers comprises a hub 8 forming a casing carrying an annular series of propeller blades 9. Each of these propeller blades is mounted upon a rod or stem 10, the rods or stems of the respective blades being radially arranged and journaled in the casing equidistantly around the hub and shaft, the construction being such that each propeller blade is mounted to turn to a determined degree in its orbit of rotation for a feathering action. 110

The mechanism for feathering the blades comprises a pinion 11 on each of the rods or stems 10, with which meshes a rack bar 12 carried by a longitudinally extending sliding controlling rod 13. The similar blades of all of the propellers of each series are arranged to be actuated by one and the same controlling rod, and the series of rods for feathering the blades of each series of propellers extend longitudinally through and are slidably mounted in the respective hubs or casings 8, each rod being normally held in a forward retracted position by springs 14 surrounding the same, between certain of the hubs 8 and abutments 15 upon the rod. At their forward ends the rods are provided with rollers 16 to traverse the surface of a stationary disk 17, which is suitably fixed to the framework 3 and is provided around a portion of its face with a cam element 18. As each series of propellers revolves with its driving shaft, the rollers of the series of controlling rods come at a prescribed point in their course of rotation in contact with the cam element 18. This cam element 18 pushes each rod back against the resistance of its contracting springs, thus moving the rack bars to impart a quarter revolution to the pinions, whereby the propeller blades are shifted to a broad-side working position throughout the working portion of their orbit of motion, the rollers of the rods at all other times traversing the plain surface of the cam disk and being held retracted by their springs, so that on the non-working portion of their orbit of movement the blades will move edgewise through the air. As a result of this construction, it will be apparent that on the outer and downward stroke of each blade for a beating action the blade will be disposed horizontally to compress the air beneath it for a lifting effect, while during the remainder of its travel the blade will extend edgewise to its plane of rotation and will thus move without material air resistance through the non-working portion of its orbit of motion.

Arranged within the car or body 1 are motors 19 which transmit motion to a common horizontal transverse driving shaft 20. Fixed to this shaft 20 is a friction driving disk 21, the opposite faces of which are engaged by friction power transmitting disks 22 and 23 feathered to slide upon and rotate with longitudinal transmission shafts 24 and 25 which are respectively connected by drive chains 26 and 27 with the propeller shafts 4 and 5, whereby said shafts 4 and 5 are adapted to be driven simultaneously in opposite directions. The disks 22 and 23 are provided with grooved collars 22' and 23' for coöperation with suitable controlling or shifting means (not shown) whereby said disks may be adjusted upon the transmission shafts to throw them into or out of en-

gagement with the friction drive disk 21 at will, or to adjust them to the same or variable degrees over the face of said drive disk with relation to its axis, by means of which the sets of propellers may be driven at any desired working speed, and also driven at different relative speeds. It will thus be understood that this series of propellers may be driven above or below sustentation speed to cause the ship to rise or descend in a controlled manner, or driven at sustentation speed to support the weight of the craft while in flight at any given elevation, or driven at different speeds for more effectively controlling the craft in balancing, banking and turning actions.

For the purpose of driving the craft ahead I provide a tractor propeller 28 mounted upon a shaft 29 having feathered thereto a sleeve 30 carrying a gear pinion 31. This pinion 31 is movable through a sliding motion of said sleeve into independent meshing engagement with gear pinions 32 and 33 on the shafts 24 and 25, or to a neutral position between said shaft gears, whereby the propeller may be driven in a clockwise or counterclockwise direction at will or entirely thrown out of action. The sliding sleeve carries a grooved collar 30' for connection with suitable shifting or controlling means (not shown) whereby the propeller gearing may be governed in an obvious manner. It will be understood, of course, that the propeller when driven in one direction will operate as a tractor and when driven in the opposite direction will act as a brake to stop or retard the forward motion of the ship, for greater convenience in controlling it in flight to avoid collisions and for other purposes. A vertical rudder 33' is provided at the stern and may be adjusted through suitable controlling means (not shown) for steering the craft to the right or left, it being evident that by the use of this rudder in conjunction with the rotary propellers, when the latter are properly governed for banking and turning actions, the machine may be steered in a ready and convenient manner. Suitably mounted upon the frame 3 are supporting planes or surfaces 34, of which any desired number may be used. In the present instance I have shown the use of two of such supporting surfaces, arranged in tandem relation one at the front and the other at the rear of the craft. Each of these supporting surfaces consists of a pair of wings 35 pivotally mounted at their inner forward corners upon driving countershafts 36 and 37, said wings being provided at their inner rearward corners with guide members 38 to travel within a grooved guideway 39, the construction being such that the wings are mounted to turn upon their shafts as centers outwardly and rearwardly to a working position and inwardly and forwardly to

a non-working position, the wings being guided in such movements as will be readily understood. When the wings are swung rearwardly they are disposed in a fully 5 opened position transversely of the craft for a supporting action, and when swung forwardly the wings will be disposed longitudinally upon the frame parallel with each other and to the line of flight, whereby the 10 wings may be thrown into action whenever it is desired to employ them in conjunction with the rotary propellers for a supporting action, and may be thrown out of operation or folded when their use is not required. 15 The shafts 36 and 37 of each set of supporting wings are provided with intermeshing gears 38' and 39' to adapt them to swing in unison, and the driving shaft 37 of each pair of wings is also provided with a beveled 20 gear 40 meshing with a similar gear 41 on a transmitting shaft 42, whereby the two shafts 36 and 37 may be rotated in unison. One of the shafts 36 and 37, as the shaft 37 of the rear wings, extends downwardly into 25 the car and is provided at its lower end with a beveled gear 43 meshing with a similar gear 44 on a longitudinally extending actuating shaft 45. This shaft 45 is adapted to be thrown, by means of a clutch device 46, into 30 and out of engagement with a shaft 47 adapted to receive motion from a shaft 48 through suitable reversing gearing arranged in a housing 49, whereby, when the clutch elements 46 are engaged, the shaft 45 may be 35 actuated to either open or close the wings. The shaft 48 is provided with a friction gear 50 to engage the disk 31 whereby it may be driven. It will, of course, be understood that the reversing gearing may be operated by a control device of any preferred 40 construction to drive the shaft 47 in the same direction as the shaft 48 or in the reverse direction, and it will also be understood that any suitable type of reversing gearing may 45 be employed.

From the foregoing description, taken in connection with the drawings, the construction and mode of operation of my improved airship will be readily understood, and it

will be seen that a construction is provided 50 which is designed to effectually perform the intended functions. While the construction disclosed is preferred, it will, of course, be understood that changes in the form, details of construction and arrangement of parts 55 may be made within the scope of the appended claims without departing from the spirit or sacrificing any of the advantages of the invention.

I claim:—

1. An airship including a body, longitudinally extending shafts on the opposite sides of the longitudinal center of the body, a series of rotary lifting propellers mounted upon each shaft, each series comprising a 65 plurality of sets of propeller blades having inwardly extending stems, spring retracted rods having rack pinion connection with the stems of correspondingly arranged blades of each series, and a stationary element co- 70 operating with each set of rods for moving the same in opposition to their springs to rotate the blades on their axes for a feathering action.

2. An airship including a body, propeller 75 shafts upon the body, lifting propellers carried by said shafts, transmission shafts in gear with the propeller shafts, a motor, gearing for driving the transmission shafts in opposite directions from the motor, gears 80 upon the transmission shafts, a driving propeller, and a gear upon the driving propeller shaft adjustable into and out of engagement with either of the aforesaid gears upon the transmission shafts. 85

3. An airship including a body, wings on independent pivots mounted upon the body for folding and unfolding actions, slotted arcuate guides described on the arcs of circles of which said pivots are centers for directing said wings in such folding and unfolding actions, propelling mechanism on the body, motor driven gearing for actuating said propelling means, and means operable by the engine for folding and unfolding 90 the wings. 95

In testimony whereof I affix my signature.
JOHN FLINK.
